UNITED STATES PATENT OFFICE.

WILLIAM C. DUNN, OF CHICAGO, ILLINOIS.

INTERNAL-COMBUSTION ENGINE.

Application filed February 5, 1925. Serial No. 7,020.

This invention relates to improvements in internal combustion engines and more particularly to what is known as the sleeve valve type, the cylinder being provided with lateral 5 inlet and exhaust ports at opposite sides thereof, the ports being controlled by slide- able sleeve members operable independently with respect to each other on the outside of the cylinder and in timed relation with the 10 other parts of the engine.

It has been customary in engines of this type to provide concentric sleeves operating exteriorly of the cylinder and during the operation a film of oil is formed between the 15 sleeves.

It is well known that in an engine of this character it is difficult to cool, and in cold weather and by reason of the oil sticking between the sleeves, it is difficult to start the 20 engine.

It is one of the objects of the present invention to overcome all of these difficulties and objections and to provide an internal combustion engine embodying a single split or 25 sectional sleeve valve for controlling the inlet and exhaust ports, the sections of the sleeve moving in opposite directions, and in which sleeve the explosion takes place to operate directly upon the piston, which latter reciprocates within and contacts with the wall of 30 the sleeve sections, with the result that a single sleeve will be provided and the engine will be easier to cool, the pressure and force of the explosion serving to assist in effectively 35 sealing the parts against the loss of fuel and compression.

To the attainment of these ends and the accomplishment of other new and useful objects as will appear, the invention consists 40 in the features of novelty in substantially the construction combination and arrangement of the several parts hereinafter more fully described and claimed and as shown in the accompanying drawings illustrating this invention and in which drawings:

Figure 1, is a vertical longitudinal sectional view through a cylinder of an engine constructed in accordance with the principles of this invention.

Figure 2, is a detail perspective view of one of the members or sections of a sleeve valve embodying this invention.

Figure 3, is a detail side elevation of the other member or section of the sleeve valve.

Figure 4, is a horizontal sectional view on line 4—4 Figure 6.

Figure 5, is a top plan view of Figure 6.

Figure 6, is a longitudinal sectional view on line 6—6 Figure 5.

Figure 7, is a top plan view of Figure 8. 60

Figure 8, is a vertical sectional view taken on line 8—8 Figure 7.

Figure 9, is a top plan view of the other member of the sleeve valve.

Figure 10, is a vertical sectional view taken 65 on line 10—10 Figure 9.

Referring more particularly to the drawings the numeral 15 designates generally a stationary cylinder adapted to be cooled in suitable manner but here shown as being provided with a water jacket 16. Fixed at one 70 end of the cylinder is a head 17 secured in position in any suitable manner such as by means of fastening bolts 18.

The head projects into the cylinder for any 75 suitable distance and is of an external diameter somewhat less than the internal diameter of the cylinder to form a space therebetween for receiving the end of a sleeve valve to be hereinafter described.

The inner end of the head is preferably 80 dome shaped as at 19 for the purpose of providing sufficient clearance or combustion space, and an ignition device 20 such as a spark plug extends through the head of the cylinder to be disposed at the top of the dome for igniting the charge introduced into the sleeve valve and between the head 17 and the piston 21.

The piston is reciprocated in the ordinary 90 manner such as by means of a connecting rod 22 connected with a crank shaft 23.

The cylinder is provided with an inlet port 24 and an exhaust or outlet port 25 preferably in alignment and at opposite sides of the 95 cylinder.

Arranged axially within the cylinder 15 is a tubular or sleeve valve in which the piston 21 works and reciprocates with respect thereto. The head 17 telescopes into the valve so that one end of the valve will reciprocate in the space formed between the cylinder 15 and the portion of the head 17 which projects thereinto, to be guided thereby.

Suitable packing rings or glands 26—27 105 may be provided and carried by the head 17, between the head and the adjacent face of the sleeve valve.

The valve is of a tubular construction and consists of two members or sections 28—29, 110 the section 28 having a portion removed therefrom to form an opening 30 laterally

through the wall thereof. The longitudinal edges of the opening 30 are beveled or inclined with respect to each other as at 31 and diverge from the outer periphery of the section 28 inwardly.

If desired the upper end of the section 28 may be annular as at 32 and the lower extremity may also be annular as at 33, that is, so that the ends of the opening 30 will terminate 10 within and be spaced from the respective extremities of the section 28. The opening 30 may be of any desired width but is preferably considerably less than one half of the circumference of the section.

15 This section 28 is provided with a lateral opening 34 adapted to be moved into and out of register with the outlet opening or port 25 as the section is reciprocated.

20 The section 29 of the valve is of a width to fill the opening 30 and the longitudinal edges 35 are beveled or inclined to correspond with the edges 31 of the section 28 so that when the section 29 is placed in position with respect to the section 28 the opening 30 in the section 28 will be closed.

25 The faces 31 and 35 on the sections 28-29 are so arranged and co-operate with each other that pressure created within the valve will tend to force the section 29 outwardly 30 with respect to the section 28 to cause the inclined or beveled co-operating faces 31-35 on the respective sections to form fluid tight joints, while at the same time the valve sections will be adapted for a free relative longitudinal movement one with respect to the other.

35 The section 29 is provided with a port or opening 36 adapted to be moved into and out of register with the port or opening 24 when the section 29 is longitudinally reciprocated.

40 The outer face of the upper portion of the member 29 is preferably cut away as at 37 and the outer face of the lower portion is also cut away as at 38 so that when the valve sections are assembled as shown in Figures 4 and 5, the upper extremity of the section 29 will project through the annular portion 32 and the lower extremity 38 will project through the annular portion 33 of the valve section 28 45 to assist in guiding the relative movements of the sections 28-29 one with relation to the other, and the inner faces of the sections 28-29 will co-incide.

45 When the valve sections are placed in position within the cylinder 15 the piston 21 will reciprocate in the valve, that is the valve will be interposed between the cylinder wall and the piston thereby producing a construction which may be more readily cooled, and at the 50 same time the sections of the sleeve valve will, when they move in opposite directions, break or tear apart any binding which might be caused or formed by oil film or otherwise between adjacent co-operating faces, especially 55 when the parts are cold.

If desired suitable lubricating openings 39 may be provided along the edges 31 of the section 28.

The section 29 of the valve with its port 36 controls the inlet port 24 while the section 28 with its port 34 controls the exhaust port 25 thereby enabling a larger port to be provided in the section 28 than would be possible to provide in the section 29.

70 The sleeve or valve sections 28-29 may be actuated from either end thereof and from either side and in any desired manner, but they are preferably operated from below the valve and on the same side.

75 To that end the sections 28-29 are respectively provided with lugs 40-41 on the sides thereof and are respectively connected through the medium of connecting rods 42-43 with a crank or eccentric shaft diagrammatically represented at 44 and which latter receives its motion from any suitable source 45 preferably through the medium of a driving element 46 such as a sprocket chain, belt or the like.

80 Obviously the sleeve or valve sections 28-29 will be actuated in timed relation with the other parts of the engine to open and close the inlet and exhaust ports according to the cycle of the engine in which they are employed.

85 This construction is particularly adapted, though not necessarily limited in its use in an engine of the four cycle type and has been so illustrated.

90 It will be manifest that with the present invention the necessity for adjusting the valves and the necessity for grinding them will be obviated as the pressure created within the valve or sleeve will operate to cause the parts to become effectively sealed against the loss or escape of compression as the action of the faces 31 and 35 of the valve sections will adapt them to become effectively seated against each other by continued and extensive use.

95 Any suitable means may be provided for lubricating the valve such as a pipe 47 which receives its supply of lubricant from any suitable source.

100 While the preferred form of the invention has been herein shown and described, it is to be understood that various changes may be made in the details of construction and in the combination and arrangement of the several parts within the scope of the claims without departing from the spirit of this invention.

105 What is claimed as new is:

110 1. An internal combustion engine including a fixed cylinder, inlet and exhaust ports, a reciprocable piston, a sectional tubular valve, said sections extending lengthwise of the valve, said valve being seated against the inner wall of the cylinder and in which valve the piston reciprocates, the pressure 115

created within the valve operating to cause the abutting surfaces of the valve sections to form fluid tight joints, and means for independently moving the valve sections for controlling the said ports.

5. An internal combustion engine including a fixed cylinder having inlet and exhaust ports, a sectional tubular valve, said sections extending lengthwise of the valve, the longitudinal edges of the sections being beveled or inclined, the proximate edges of adjacent sections having sliding contact, a reciprocable piston, and means for independently moving said sections for controlling said ports, the pressure created within the valve operating to cause the contacting surfaces of the valve sections to form fluid tight joints.

10. An internal combustion engine including a fixed cylinder having inlet and exhaust ports, a sectional tubular valve, said sections extending lengthwise of the valve, the longitudinal edges of the sections being beveled or inclined, the proximate edges of adjacent sections having sliding contact, a reciprocable piston, and means for independently moving said sections for controlling said ports, the pressure created within the valve operating to cause the contacting surfaces of the valve sections to form fluid tight joints, the extremities of one of said sections being annular and through which annular portions the extremities of the other section reciprocates.

15. An internal combustion engine including a fixed cylinder having oppositely disposed inlet and exhaust ports, a reciprocable piston, a sectional tubular valve, said sections being seated against the inner wall of the cylinder, the proximate longitudinal edges of the sections being beveled and having sliding contact, said piston reciprocable

within the valve, and means for independently moving the valve sections for controlling said ports, the pressure within the valve operating to cause the contacting edges of the 45 said sections to seal the joints therebetween.

20. An internal combustion engine including a cylinder having oppositely disposed inlet and exhaust ports, a pair of oppositely disposed curved valve members having beveled longitudinal edges, the proximate longitudinal edges of said members having sliding contact, said members being seated against the inner wall of the cylinder, and means for independently moving said members, the cylinder pressure tending to laterally separate the said members to cause the abutting edges thereof to form fluid tight joints therebetween.

25. An internal combustion engine including a cylinder having oppositely disposed inlet and exhaust ports, a pair of oppositely disposed curved valve members having beveled edges, the proximate longitudinal edges of said members having sliding contact, 65 said members being seated against the inner wall of the cylinder, means for independently moving said members, the pressure in the cylinder tending to laterally separate the said members to cause the abutting edges 70 thereof to form fluid tight joints therebetween, a head for the cylinder extending between the valve members, and a piston reciprocable within the valve members, said members co-operating with the cylinder head 75 and piston to constitute an explosion chamber.

In testimony whereof I have signed my name to this specification, on this 2nd day of February, A. D. 1925.

WILLIAM C. DUNN.
